UNITED STATES PATENT OFFICE.

MOSES BOMBERGER, OF CUMRU TOWNSHIP, BERKS COUNTY, PENNSYLVANIA, ASSIGNOR
TO ORR & SEMBOWER, INC., OF READING, PENNSYLVANIA.

SPARK AND EXHAUST MECHANISM FOR EXPLOSIVE-ENGINES.

1,265,876.

Specification of Letters Patent.

Patented May 14, 1918.

Application filed July 27, 1916. Serial No. 111,561.

To all whom it may concern:

Be it known that I, MOSES BOMBERGER, a citizen of the United States, residing at Mountain View Hotel, Cumru township, in the county of Berks and State of Pennsylvania, have invented certain new and useful Improvements in Spark and Exhaust Mechanism for Explosive-Engines, of which the following is a specification.

10 My invention relates to speed regulating mechanism for explosive engines, and consists in the improved spark and exhaust controlling means hereinafter fully described in connection with the accompanying drawings, the novel features of which are particularly pointed out in the claim.

Figure 1 is a side elevation of a vertical explosive engine having my invention applied thereto in connection with known controls, the novel features of which are particularly pointed out in the claim.

Fig. 2 is a partial end view; both the fly-wheel and governor being shown.

25 Fig. 3 is a separate sectional view of the timing gear with its exhaust-control cam and spark-control contact.

Fig. 4 is a plan view of the combined spark-and-exhaust control lever; and Figs. 30 5 and 6 are separate views of its separately formed parts.

The drawing illustrates an explosive engine comprising a cylinder 2 having a water jacket and tank extension 3, 4, and inlet and exhaust valves as usual, the latter being provided with a depending stem 5 through which it is operated; a supporting frame 7, with crank shaft 8 mounted therein and provided with a fly-wheel 9 carrying a centrifugal governor arm 10; a lever 11 arranged to engage the exhaust valve stem 5; a timing gear 12 carrying a cam 13 operative upon said lever 11; and a governor-controlled latch 15, 16 for said lever.

45 All of the above-mentioned parts are broadly old and well known in explosive engines; my invention consisting particularly in the improved construction herein-after fully described, the main object of 50 which is to provide simple and advantageous means for properly controlling the sparking and exhaust.

The lever 11 is shown pivoted as usual at

a fixed point 20; with one end thereof arranged to lift the exhaust-valve stem 5 when 55 itself raised by the timing-wheel cam 13, and its other end 21 preferably adapted to operate a pump, not shown. The governor controlled latch 15 is adapted, as usual, to hold the lever and exhaust valve in fully 60 raised position while the determined speed is exceeded, said latch 15 being acted upon by the centrifugally swung governor 10 through the spring-connected latch-arm 16. In my improved construction this operating 65 lever 11 for the exhaust valve carries a separately formed spark-control contact attachment 25; the latter being rigidly fixed to the lever with suitable insulation therefrom as indicated at 26, and being connected to the 70 sparking wire 27 extending to the usual sparking plug, not shown; so that the contact point 28 of said rigid attachment is swung up or down with the lever as the latter is raised or lowered by the passing of the 75 timing-wheel cam 13 at each revolution of said wheel, and is held in raised position by the lever latch 15 when the latter is thrown into action by the governor 10. And the rotary-timing-wheel 12 is provided not only 80 with said exhaust-control cam 13 for operating the lever 11, but also with a circuit-making contact 30 adapted to make passing sparking connection with the lever-carried contact point 28 when the lever is lowered 85 from its raised position indicated in Fig. 1, to its normal lowered position upon the hub of timing gear 12. This contact 30 is fixed to the timing wheel by means of a slotted connection 32, as indicated, so as to permit 90 of any desired adjustment. It is swung past the lever-carried contact point 28 without making sparking connection, when the lever is in raised position; and when the latter is in lowered position such passing connection 95 is made without exerting any lifting action upon the exhaust valve, this latter being effected solely by the exhaust-control cam 13. My improved mechanism is advantageously 100 simple and free from liability of derangement, as well as positive and reliable in operation, and the construction specifically set forth may be modified within the scope of the invention as defined in the claim.

What I claim is:

In an explosive engine, the combination

of an exhaust valve, a rotary timing wheel carrying an exhaust-control cam and an adjustably fixed spark-control contact, an interposed pivotally mounted valve-operating lever having a circuit-making contact piece insulatedly fixed thereto, and a governor controlled latch for said lever; said timing

wheel contact being adapted to raise the lowered lever in making circuit, and to clear the lever contact piece when the lever is in latched position, substantially as set forth.

In testimony whereof I affix my signature.

MOSES BOMBERGER.
